UNITED STATES PATENT OFFICE.

MILTON JACKSON, OF PHILADELPHIA, PENNSYLVANIA.

DESIGN FOR A PADLOCK.

SPECIFICATION forming part of Design No. 20,016, dated July 15, 1890.

Application filed June 18, 1890. Serial No. 355,903. Term of patent 14 years.

To all whom it may concern:

Be it known that I, MILTON JACKSON, a citizen of the United States, and a resident of Philadelphia, Pennsylvania, have invented a new and original Design for a Padlock, of which the following is a specification.

My design is fully shown in the accompanying drawings, in which—

Figure 1 represents a side view of the lock, and Fig. 2 an end or edge view of the same.

In outline the body of the lock is reversely tapered—that is to say, it is expanded slightly from the top to a point some distance below the top and is then contracted slightly to the bottom. This outline, however, is a minor and unessential feature of the design, the main feature of which is the ornamentation

of the body of the lock. This ornamentation consists of end bands *a* and cross-bands *b*, *d*, and *f*, inclosing roughened or pitted portions or panels *g* and *h*. The top bands *b* have central extensions *i*, rounded in outline and projecting down into the top panel *h*.

I claim—

The design for the body of a padlock, substantially as described, and as shown in the accompanying drawings.

In testimony whereof I have signed my name to this specification in the presence of two subscribing witnesses.

MILTON JACKSON.

Witnesses:

EUGENE ELTERICH,
HARRY SMITH.
